UNITED STATES PATENT OFFICE.

CHARLES STRIER, OF BROOKLYN, NEW YORK, ASSIGNOR TO JENNIE STRIER, OF BROOKLYN, NEW YORK.

HAIR COMB.

Application filed August 17, 1921. Serial No. 493,051.

To all whom it may concern:

Be it known that I, CHARLES STRIER, a citizen of the United States, and a resident of Brooklyn, borough of Brooklyn, in the 5 county of Kings and State of New York, have invented a new and Improved Hair Comb, of which the following is a full, clear, and exact description.

This invention relates to a hair comb, 10 primarily designed for use with bobbed hair.

An object of the invention is to provide means for holding the hair in position and preventing the same from falling about 15 the face.

Other objects of the invention will be clearly understood from the following detailed description and accompanying drawings.

20 Figure 1 shows the comb attached to the hair.

Figure 2 is a perspective view of the comb showing it with barrettes attached.

Referring to the above mentioned drawings, a resilient band 10 has a curved comb 11 attached thereto. Attached to each end 25 of the resilient band 10 are barrettes 12 and 13. These barrettes have in conjunction therewith clasps 14 and 15 for attaching the comb to the hair. The barrettes are sometimes set with stones, as shown in 30 16. These barrettes may be rigidly attached to the band 10 or they may be pro-

vided with means for detachably connecting them to the band. Furthermore the bar- 35 rettes might be made integral with the band 10.

In applying this comb to the hair, the barrettes 12 and 13 are first attached to the band 10, then the band is placed about the 40 head as shown in Figure 1, with the teeth of the comb 11 projecting downward and engaging with the hair. The barrettes 12 and 13 are then attached to that portion of the hair nearest the face. Thus the hair 45 is held from falling in front of the face and the hair about the back of the head is held down in position by the band 10 and the comb 11.

I would state in conclusion that while the 50 illustrated examples constitute the practical embodiments of my invention, I do not limit myself strictly to the exact details herein illustrated, since manifestly the same can be considerably varied without 55 departing from the spirit of my invention as defined in the appended claim.

What I claim is:—

As a new article of manufacture, a hair comb of the class described, comprising a 60 resilient band, a curved comb for engaging the hair to retain it in position carried by the band, and barrettes provided with means for positively gripping the hair attached to the resilient band.

CHARLES STRIER
